Patented Sept. 29, 1914.

UNITED STATES PATENT OFFICE.

PHILIP HAAS, OF DAYTON, OHIO.

FLUSHING DEVICE FOR WATER-CLOSETS.

1,111,745.

Specification of Letters Patent. Patented Sept. 29, 1914.

Application filed June 12, 1912. Serial No. 703,346.

To all whom it may concern:

Be it known that I, PHILIP HAAS, citizen of the United States, residing at Dayton, in the county of Montgomery and State of Ohio, have invented certain new and useful Improvements in Flushing Devices for Water-Closets; and I do hereby declare the following to be a full, clear, and exact description of the invention, such as will enable others skilled in the art to which it appertains to make and use the same.

My present invention relates to the class of automatic flushing devices for water closets and consists in an improved construction of valve mechanism releasing and controlling the passage of water to the bowl.

In the drawings I have shown the best form in which I have contemplated embodying my invention and the said invention is hereinafter fully described and its novel features pointed out in the specification and claims.

In my said drawings, Figure 1 is a vertical elevation partly in section. Fig. 2 is a horizontal section on dotted line 2—2, Fig. 1. Fig. 3 is a vertical section on line 3—3, Fig. 1. Fig. 4 is a partial longitudinal vertical section of the main body or casing.

In these figures of drawing, A represents the casing or body of my improved flushing valve or device, which is hollow and provided with a cylindrical pressure chamber a^2 , having a removable cap or closure G at its outer end. The casing is also provided with a cylindrical guiding chamber a^4 in axial alignment with the pressure chamber a^2 , which is closed by a similar removable cap or closure G'. Within the casing or valve body is a partition a^5 disposed transversely to the axis of the pressure chamber and the guiding chamber and interposed between them, the said partition being provided with a central aperture a^3 substantially in axial alignment with the axis of the pressure chamber and guiding chamber. The casing is also provided with an inlet chamber a which communicates by a passage a' with the guiding chamber, on one side of the partition, and the valve casing is also provided with an outlet chamber a^8 which communicates by a passage a'' with the pressure chamber a^2 , on the other side of the partition a^5 . Within the pressure chamber is located a piston B fitted therein and provided with a concentric stem b , which is adjustable with respect to the pis-

ton, in this instance being screw threaded and screwed into a threaded aperture in the piston and secured in adjusted position by set nut b' . This piston carries a valve B' which is adapted to engage portions of the partition a^5 surrounding the aperture a^3 and close said aperture when the piston is at the inner end of the chamber. In the guiding chamber a^4 I provide a guiding body C which fits easily therein and is preferably provided with a plurality of peripheral grooves or notches C² which afford a constant communication between the water inlet and that portion of the guiding chamber on the outer side of the guiding body C. This guiding body is provided at its inner face with a valve or washer c' which engages the face of the partition a^5 surrounding the aperture a^3 and normally closes said aperture, the guiding body being held in this position by the pressure of the water on the outer face of the guiding body in the guiding chamber a^4 . The guiding body C also carries on its inner face a cylindrical valve B² which projects beyond the valve c' and normally fits within the aperture a^3 . The guiding body C is movable with respect to the piston, but is actuated by the stem b thereof, the said guiding body C having a central bore or recess which receives the stem b with an easy fit so as to permit of relative movement between the body C and the stem b longitudinally of the stem, as indicated in dotted lines in Fig. 2. The valve casing is also provided with a rounded projection D. Within this projection is located the valve E and a passage g connects this valve with the inlet chamber a . The valve E is mounted on a stem e extending above and below the valve. Below the valve this stem extends downward through a passage d in the projection D and through a stuffing box at the bottom of the same. Below the stuffing box the stem is provided with a cap e' to be engaged when the valve E is to be raised. A spring f is provided to draw down the stem and close the valve when the stem is released from the pressure which raises it.

The passage d is connected by a passage g' with the pressure chamber a^2 in rear of the piston B and the passage d just below the valve E is enlarged downward to the said passage g' so that when the valve is raised water will readily flow from the valve to the said passage. The remaining

portion of the passage d is of less size but still is larger than the stem of the valve and provides a reduced passage for water to flow through. A space d' just above the stuffing box is connected with the water outlet by a passage g^2 .

- The operation of this device is as follows: The arrangement of the device is such that when pressure is placed upon the seat of the closet a part connected therewith (not shown) will press upwardly upon the cap e' and raise the valve E . Water will then enter the passage g from the inlet chamber, pass below the valve E into the passage d and downward in said passage and through the passage g' into the pressure chamber a^2 behind the piston B . The outer end of the rod b connected therewith normally rests at a predetermined distance from the bottom of the opening in the valve B^2 and the movable guiding body C and, therefore, the piston and its connected valve will, at the time determined upon, move the said valve and movable guiding body C . As soon as the valve B^2 leaves the opening a^3 water will flow from the inlet chamber a through the opening a^3 down through the outlet chamber a^x into the bowl for the preliminary flushing of the latter. This flow continues only until the valve B' closes the opening a^3 . This is only for a short time as the piston in this movement moves with considerable rapidity. When the valve B' has closed the opening a^3 the valve B^2 will have been moved a distance away from the said opening. In this position of the parts no water passes to the bowl except such as passes downward through the passage d around the stem of the valve E .
- When the seat is relieved of pressure the valve E drops and closes the upper part of the passage d relieving the rear of the piston B from pressure. The pressure on the face of valve B' forces this valve and piston backward as fast as the water in rear of said piston can flow out through the passages g' , d , space d' into the water outlet. As soon as the valve B' moves from the opening a^3 water from the water supply flows through said opening into the chamber a^x and through the water outlet into the bowl flushing the same. This flow continues until the valve B^2 closes the said opening a^3 . This movement is caused by the draw of the rod b , the suction of the outflowing current, and pressure of the water supply.
- The length of the flushing of the bowl is regulated by the distance between the face of the valve B' and the valve B^2 . This distance can be increased or diminished by adjusting the rod in the connected valve and piston body, and this can be accomplished at any time when the parts are in their normal positions by removing the cap G closing the outer end of the pressure cham-

ber a^2 . The aperture a^3 being then closed by the valve B^2 the piston body can now be removed, the lock nut b' loosened and the rod b moved to the position desired and secured by the lock nut.

What I claim and desire to secure by Letters Patent is:—

1. In an automatic flushing valve for water closets, the combination with a hollow main casing provided with a compression chamber at one end and a guiding chamber at the other end, in axial alinement therewith, said chambers being separated by a partition having an aperture therein, said casing being provided with a water inlet communicating with the inner end of the guiding chamber on one side of the partition, and with a water outlet communicating with the inner end of the compression chamber on the other side of the partition, of a movable guiding body fitting said guiding chamber, a valve carried thereby normally closing the aperture in the partition, a piston in the compression chamber, a valve normally in open position carried by said piston for closing the aperture in the partition, a part extending through the aperture in the partition and connecting said guiding body and piston, means for maintaining a constant communication between the outer end of the guiding chamber and the water inlet, a by pass connecting the water inlet with the outer end of the compression chamber, an auxiliary valve controlling said by-pass, and said casing being provided with a reduced passage from said by-pass, between said auxiliary valve and the outlet chamber, to said outlet chamber for discharging water from said compression chamber on the outer side of the piston, whereby on the opening of said auxiliary valve, water is admitted behind the piston to move said guiding body and piston and open the aperture in the partition to produce a preliminary discharge of water through the valve casing, which is cut off by the piston valve, and whereby on the closing of said auxiliary valve, the accumulation of water in the guiding chamber behind the guiding body moves said guiding body and piston in the reverse direction and produces a flushing discharge through the valve casing, which is cut off by the closing of the valve carried by said guiding body.
2. In an automatic flushing valve for water closets, the combination with a hollow main casing provided with a compression chamber at one end and a guiding chamber at the other end, in axial alinement therewith, said chambers being separated by a partition having an aperture therein, said casing being provided with a water inlet communicating with the inner end of the guiding chamber on one side of the partition, and with a water outlet communicating with the inner end of the compres-

sion chamber on the other side of the partition, of a movable guiding body fitting said guiding chamber, a valve carried thereby normally closing the aperture in the partition, 5 a piston in the compression chamber, a valve carried thereby for closing the aperture in the partition, said piston and guiding body being provided, the one with an adjustable stem loosely engaging the other and extending through the aperture in the partition, a bypass connecting the water inlet with the outer end of the compression chamber, an auxiliary valve normally closing said bypass, said casing being provided 10 with a passage from the outer end of the compression chamber to the water outlet, and means for maintaining a constant communication between the outer end of the guiding chamber and the inlet chamber, 15 whereby on the opening of said auxiliary valve, the piston operates said movable guiding body to open the partition aperture and produce a preliminary passage of water through the casing, which is cut off by the piston valve and on the closing of the auxiliary valve, the guiding body operates to open the piston valve and produce a flushing passage of water through the casing which is cut off by the closing of the valve 20 carried by said guiding body.

3. In an automatic flushing valve for water closets, the combination with a hollow main casing provided with a compression chamber, said main casing being provided 25 with a guiding chamber in axial alignment with the pressure chamber and separated therefrom by a partition having an

aperture therein, said casing having an inlet chamber communicating with the guiding chamber on one side of said partition, 40 and an outlet chamber communicating with the compression chamber on the opposite side of said partition, and a by-pass from the inlet chamber to the outer end of the pressure chamber, of a guiding body fitting 45 said guiding chamber, a valve carried thereby normally closing said aperture in the partition, a piston in the pressure chamber, a valve carried thereby for closing the aperture in the partition, a stem secured to said 50 piston and loosely engaging said guiding body, an auxiliary valve normally closing said bypass, means having a part outside the casing for opening said auxiliary valve, and means for maintaining a constant communication between the outer end of the guiding chamber and the inlet chamber, said 55 stem being adjustable to vary the relative positions of the piston and guiding body, and regulate the duration of the flushing, 60 said casing having a removable closure at the outer end of the pressure chamber, whereby said closure can be removed and the piston and its stem withdrawn to adjust the stem to vary the duration of flush 65 and replaced, without cutting off the water supply to the inlet chamber.

In testimony whereof I affix my signature, in the presence of two witnesses.

PHILIP HAAS.
